UNITED STATES PATENT OFFICE

ALFRED HENRY COUSINS, OF LEICESTER, ENGLAND, ASSIGNOR TO UNITED SHOE MACHINERY CORPORATION, OF PATERSON, NEW JERSEY, A CORPORATION OF NEW JERSEY

FINISHING TOOL

Application filed November 23, 1929, Serial No. 409,371, and in Great Britain December 15, 1928.

This invention relates to finishing tools and is herein illustrated as embodied in a tool for finishing surfaces of heels.

It is a general practice of shoemaking in finishing heels to burnish that curved surface between the tread and attaching faces thereof at the sides and rear portion, which is herein termed the "peripheral face," and also that exposed surface of the heel portion of a shoe forming a boundary of the rand crease as well as to impart a series of indentations in a line parallel with the rand crease about the peripheral face of the heel.

So far as applicant is aware, it has been necessary in the past to submit a heel to be thus treated to two separate operations which have been accomplished by the use of a tool primarily for performing the burnishing operation and another for performing the indenting operation. Although some tools used heretofore for indenting heels have been provided with a guide adapted to engage the lower rand crease bounding face and incidentally serving as a means for burnishing it and other tools have been constructed to burnish simultaneously both this face and the peripheral face, no attempt to combine the indenting feature in a heel burnishing tool such as that disclosed herein has met with success prior to applicant's invention.

It is, therefore, an object of this invention to provide an improved finishing tool for burnishing the peripheral face of a heel and having means for indenting it, both of which operations are done upon a single transfer of the point of contact of the tool and the heel thereabout. In accordance with this object of the invention and in accordance with one feature thereof, the illustrated tool is provided with a burnishing surface adapted for engagement with the peripheral face of a heel along a transverse section and an indenting wheel mounted at one side of said tool whereby as a heel is progressively presented to the tool the indenting is effected

on a previously burnished surface. By presenting the work in tangential relation to both the burnishing surface and the indenting tool, different portions of the work are both burnished and indented simultaneously, the indenting means operating on successive portions of the work which have been burnished and which are progressively presented to the tools, thereby insuring that the peripheral face of the heel shall be completely burnished and indented with one passage of the point of operation of the tool on the heel thereabout.

In accordance with another feature of the invention, the illustrated indenting means comprises a wheel which is rotatably mounted and arranged to protrude from the adjoining burnishing element and, being at one side thereof, a heel may be presented in normal relation to either the indenting means or to the burnishing element at one side thereof if it is desired to utilize the tool in only one of its capacities.

In accordance with another feature of the invention, a lip arranged to extend from the tool at one extremity of its burnishing surface is shaped for engagement within the rand crease of a shoe in order to serve as a guiding means for the tool and to provide a surface for burnishing the lower rand crease bounding face. It will now be apparent that the illustrated tool is constructed for complete engagement with the heel portion of a shoe heightwise thereof along any transverse section, and that the entire exposed portion of the side and rear faces of the heel may be finished with one transfer of the point of contact of the tool and the work thereabout.

In the accompanying drawing,

Fig. 1 is a side elevation showing a tool in which the invention is embodied in operative relation to a shoe;

Fig. 2 is a plan view of the tool and shoe as illustrated in Fig. 1;

Fig. 3 is an end elevation of the tool shown in Fig. 1; and

Fig. 4 is a fragmentary plan view of the tool with parts removed and broken away.

The illustrated tool comprises a body 10 from one end of which extends a shank 12 which is adapted for engagement within a corresponding recess in the head of a burnishing machine, which head may be vibrated to operate the tool, as indicated by the arrows in Fig. 2, or may be held stationary as desired. The outer end of the tool body 10 is convexly rounded and polished to provide a burnishing surface 14 which is shaped for engagement with the peripheral face of a heel to be operated on. As herein shown, vertical elements of this surface are substantially straight, making it particularly well adapted for operating on heels of men's shoes, but it should be understood that this burnishing surface may be constructed in accordance with the shape of any heel to be operated on without departing from the spirit of this invention. A lip 16 extending from the upper portion of the tool body 10, as illustrated in Fig. 1, has a burnishing surface 18 angularly disposed with respect to the surface 14 and is adapted for engagement within the rand crease of the shoe to be operated on and to burnish the surface of the heel portion thereof forming the lower boundary of the rand crease as well as to provide a guide for the burnishing tool.

The tool body 10 is slotted longitudinally thereof in its central portion as at 20 to receive an indenting heel 22 which is arranged to protrude beyond the peripheral face of the burnishing surface 14 of the tool body. The illustrated indenting wheel 22 is rotatably mounted toward one side of the tool body to facilitate the presentation of the work either simultaneously or alternately to the burnishing and indenting means, as indicated in Fig. 2, on a stud 24 firmly fixed to a plate 26 which may be adjustably secured to the tool body by means of a screw 28. To permit adjustment of the indenting wheel, the tool body is recessed, as at 30, to provide clearance for the stud 24, and the plate 26 is provided with an elongated slot 32, both of which slots allow the plate 26 and hence the indenting wheel 22 to be moved toward and from the burnishing surfaces 14, 18 of the tool body and also, to some extent, sidewise of the tool body 10. It will be apparent from an inspection of Figs. 3 and 4 that the right-hand portion of the burnishing surface of the tool is continuous or uninterrupted along transverse sections so that all of the peripheral face of a heel, including the portion which is to be beaded or indented, when properly presented to the tool, will receive a burnishing treatment.

In the ordinary use of the tool, a heel is presented thereto in engagement with both

the burnishing surfaces 14, 18 at the right-hand portion thereof and also in engagement with the indenting wheel 22, the lip 16 being inserted in the rand crease of the shoe and the burnishing surface 18 bearing against the corresponding face of the heel, thereby to burnish it as well as to guide the tool. As above stated, the burnishing tool may be either vibrated in a manner well known in the art or held stationary. The operator then moves the shoe, holding it first in engagement only with the burnishing surface of the tool as above described until the indenting operation is to be started, at which time the shoe is held to establish engagement between its heel and both the burnishing surface and the indenting means. The work ordinarily being turned in a clockwise direction (Fig. 2), with respect to any point on the heel's surface, the heel will first be burnished and then indented; but it is to be understood that the burnishing and the indenting of the heel are carried out simultaneously during a greater portion of the finishing operation, although at any instant the burnishing and indenting operations are being performed at different points on the heel.

It will also be apparent that by presenting the work in normal relation to either the indenting wheel alone or to only the burnishing surface at one side of the indenting wheel, the work so presented may either be indented or burnished.

It will now be apparent that a heel may both be completely burnished and simultaneously indented with one transfer of the point of contact of the tool and the heel thereabout by the use of a tool such as that disclosed herein, or that it may be used either as a burnishing tool or as an indenting tool at the discretion of the operator.

Having described my invention, what I claim as novel and desire to secure by Letters Patent of the United States is:

1. A tool for finishing a heel upon a single transfer thereabout of the point of contact of the tool therewith, said tool having a work engaging surface arranged to burnish the entire peripheral face of the heel, and means disposed at one side of said surface for indenting the heel whereby the indenting is effected on a previously burnished surface as successive portions of the heel surface are progressively presented to the tool.

2. A tool for finishing heels upon one transfer thereabout of the point of contact of the tool therewith, said tool having uninterrupted burnishing surfaces adapted for complete engagement with both the lower bounding surface of the rand crease and the peripheral face of a heel along a transverse section thereof and having means for indenting the said peripheral face of the heel.

3. A finishing tool having work engaging faces adapted for complete engagement with

the heel portion of a shoe heightwise thereof along a transverse section and having means for indenting the peripheral face of the heel arranged to operate simultaneously with the 5 burnishing of the heel by said surfaces but on successive previously burnished portions of the heel held in tangential engagement with said indenting means and burnishing surfaces.

- 10 4. A finishing tool comprising burnishing surfaces adapted to engage both the lower bounding face of the rand crease and the peripheral face of a heel and having indenting means protruding from the peripheral face 15 burnishing surface of the tool at one side thereof whereby the indenting means is caused to operate simultaneously with the burnishing surface but on a previously burnished portion of the heel as it is progressively 20 presented to the tool in tangential relation to said indenting means and said peripheral face burnishing surface.

5. A finishing tool comprising burnishing surfaces adapted for complete engagement 25 with both the lower rand crease bounding face of a heel and the peripheral face thereof along a transverse section, and means for indenting the peripheral face of the heel protruding from one of said burnishing surfaces 30 at one side thereof whereby a shoe by being presented in normal relation to the tool at either said indenting means or at one side thereof may be either indented or burnished.

35 6. A tool for finishing heel faces comprising intersecting burnishing surfaces adapted for complete engagement along a transverse section with the lower rand crease bounding face and the peripheral face of a heel and having an indenting wheel at one side of and protruding from said peripheral face burnishing surface whereby the pressure against the tool of a heel presented in tangential relation both 40 to said wheel and burnishing surface is distributed between the indenting wheel and the burnishing surface.

45 7. A tool for finishing heel faces comprising a burnishing surface adapted for complete engagement with the peripheral face thereof along a transverse section, a lip extending from said surface arranged to enter the rand crease between the upper of a shoe and the heel thereof, said lip having a burnishing surface for engagement with the lower rand crease bounding face and a rotatable 50 indenting wheel protruding from said peripheral face furnishing surface at one side of said tool.

55 8. A tool for finishing heel faces comprising burnishing surfaces adapted for complete engagement along a transverse section of both the lower rand crease bounding face and the peripheral face of a heel and having an indenting wheel for operating on the peripheral face of the heel arranged to be adjustably 60 clamped at one side of said tool.

9. A tool for finishing heel faces comprising angularly disposed burnishing surfaces adapted for complete engagement along a transverse section of both the lower rand crease bounding face and the peripheral face 70 of a heel and having an adjustably mounted indenting wheel arranged to protrude from said peripheral face burnishing surface, and means for securing said indenting wheel in adjusted position.

In testimony whereof I have signed my name to this specification.

ALFRED HENRY COUSINS.
